CLAIM

The ornamental design for a combined electric guitar tuning light display and component housing therefor, as shown and described.

DESCRIPTION

FIG. 1 is a top, front perspective view of a combined electric guitar tuning light display and component housing therefor showing my new design;

FIG. 2 is a rear perspective view thereof;

FIG. 3 is a side elevational view thereof;

FIG. 4 is a bottom plan view thereof; and,

FIG. 5 is a side elevational view opposite to that shown in FIG. 3.

The broken line showing of an electric guitar is for illustrative purposes only, and forms no part of the claimed design.
